Patented Mar. 19, 1929.

UNITED STATES PATENT OFFICE.

ROBERT S. LANE, OF WOOD RIVER, ILLINOIS, ASSIGNOR TO STANDARD OIL COMPANY, OF WHITING, INDIANA, A CORPORATION OF INDIANA.

REMOVAL OF WAX FROM HYDROCARBON OILS.

No Drawing.

Application filed January 2, 1926. Serial No. 79,004.

This invention relates to the separation of petrodatum from wax bearing oils, particularly residues, such as cylinder stocks, and lubricating distillates.

5 According to the present invention the wax bearing oil to be treated is thoroughly mixed with a diluent liquid comprising a mixture of naphtha, butyl alcohol and acetone, and subjected to a low temperature 10 whereupon the petrodatum or wax is removed by settling or by centrifuging or in other suitable manner. In some cases the naphtha may be omitted and a diluent consisting of butyl alcohol and acetone 15 employed.

The diluent mixture may suitably contain from 35 to 60% of naphtha, from 25 to 35% of butanol and from 12 to 35% of acetone. Thus, the following mixtures have been 20 found suitable for the present invention.

Example 1, naphtha 50%; butanol 30%; acetone 20%.

Example 2, naphtha 58%; butanol 29%; acetone 13%.

25 Example 3, naphtha 44%; butanol 29%; acetone 27%.

Example 4, naphtha 37%; butanol 30%; acetone 33%.

In carrying out the invention the diluent 30 mixture is mixed with the oil to be treated, for example, a cylinder stock, in the proportion of from 50 to 75% of the diluent to 50 to 25% of the oil. The mixture is then slowly settled and cooled to a temperature 35 of 20° F. or lower. The wax settled out, may be removed by gravity, or if desired by centrifuging. The wax-free oil is separately withdrawn, the diluent removed by distillation and the oil thereafter is finished 40 in any suitable manner. Owing to the solubility of water in acetone, it is preferred to distill the solvent off with either closed coil steam or by circulating hot oil through coils in the still until a large percentage of 45 the solvents have been removed, that is, until the butanol and acetone have been almost entirely distilled. Thereafter open steam may be introduced to remove the heavier

ends of the naphtha and to secure an oil of the desired flash point. 50

As an example of the operation of the process, a cylinder stock obtained by the reduction of mid-continent crude, having a gravity of 21° A. P. I. and a chill point of 75° F. was mixed with a diluent such as 55 that described in Example No. 1 above, in the proportion of 25 parts of the oil to 75 parts of the diluent. The mixture was cooled and settled at 10° F., the petrodatum free oil withdrawn, and upon reduction to 60 a gravity of 21.3° A. P. I. and a flash point of 520° F., showed a chill point of 15° F.

Although the present invention has been described in connection with the details of a specific embodiment thereof, it is not intended that such details shall be regarded as limitations upon the scope of the invention, except in so far as included in the accompanying claims. 65

I claim:

1. The method of removing petrodatum 70 from oil comprising the admixture of the oil with a diluent containing butanol and acetone, cooling the mixture and separating the wax from the diluent oil.

2. The method of removing petrodatum 75 from oil comprising the admixture of the oil with a diluent containing naphtha, butanol and acetone, cooling the mixture and separating the wax from the diluted oil by 80 the difference in their specific gravities.

3. The method of removing petrodatum 85 from oil comprising the admixture of the oil with a diluent containing 35 to 60% of naphtha, 25 to 35% of butanol and from 12 to 35% of acetone, cooling the mixture, and separating the wax from the diluted oil by the difference in their specific gravities.

4. A diluent mixture for the removal of 90 petrodatum from oil containing 35 to 60% naphtha, 25 to 35% butanol and 12 to 35% acetone.

5. A diluent mixture for the removal of 95 petrodatum from oil containing 50% naphtha, 30% butanol and 20% acetone.

ROBERT S. LANE.
